UNITED STATES PATENT OFFICE.

PHILIP MUELLER, OF DECATUR, ILLINOIS, ASSIGNOR TO ADOLPH MUELLER, TRUSTEE, OF DECATUR, ILLINOIS.

STRAINER SCREEN AND METHOD OF MAKING SAME.

Application filed October 24, 1925. Serial No. 64,695.

The present invention relates to strainer screens such as are used in strainers of the type disclosed in my Patent No. 1,370,147, dated Mar. 1, 1921, and it has for its object 5 to provide a screen blank, a screen, and a method of making the same by which screens can be produced at reasonable cost, both with respect to mechanical operation and stock, with a resulting efficient and dependable 10 screen structure, the replacement of which may be effected at small cost.

In order that the development may be clear to those skilled in the art, I have shown in the accompanying drawings one physical 15 embodiment of my invention, but this is merely illustrative of the invention and not restrictive.

In said drawings:

Fig. 1 is a view of a blank from which the 20 screen is made.

Fig. 2 is an edge view to show one step in the method of forming the screen.

Fig. 3 is a similar view showing the screen 25 in process of formation.

Fig. 4 illustrates another step of the method.

Fig. 5 is a view in vertical section of the completed screen.

Referring to the drawings by numbers, 30 like numbers indicating like parts in the several views, Fig. 1 shows the blank 10 from which the screen is formed. The blank 10 is cut as shown from any suitable screen stock of appropriate mesh, and is preferably 35 formed in substantially the shape of a sector of a band with curved lower and upper edges, and straight ends, although it may take other shapes. The upper edge of this sector is cut as shown, so as to give a series of leaves or 40 foliations 11, the tips of which are rounded as at 12. The ends 13 and 14 of the blank will project beyond the line of the leaves 11, one of these ends 14 projecting to a greater extent than the other, so as to provide stock 45 for forming the interlocked seam of the completed strainer, all as will appear hereinafter.

The blank thus formed will be bent as shown in Fig. 3, where the method of bending the blank in its initial step is indicated. 50 As there shown, the leaves 11 will be infolded so as to lap, one over the other, so that, when

brought to final position, they will overlie each other and close the top of the screen. Owing to the fact that the blank 10 in the preferred form, is cut as a sector of a band, it 55 will take, in its completed form, a conical shape, the top of which, as stated, is closed by the infolded, overlapped leaf section 11.

The end 13 of the blank 10, as shown in Figs. 2 and 3, will be bent up substantially at 60 right angles to the body of the blank, while the extended end 14 will be bent upwardly at substantially right angles, and then its extreme end bent downwardly so as to form an interlocking seam 15 to receive the end 14 of 65 the blank. When the screen is brought to its final form for side seaming, the end 13 will be bent downwardly and hooked into engagement with the seam 15 of the extended end 14, as shown in Fig. 4, and in this form placed 70 upon a mandrel 16 having a groove 17 to receive the interlocked ends 13 and 14 of the screen. In this position of the screen upon the mandrel, the interlocked seam will be subjected to the pressure of an appropriate 75 tool 18 of proper contour to compress and set the seam, and owing to the fact that the groove 17 of the mandrel receives the seam, the compression of the tool 18 will force the seam interiorly of the screen and leave the 80 screen with its outer surface in a smooth unbroken circumference so as to avoid any crevices in which matter suspended in the water flowing through the screen can lodge and collect, and ensure an unbroken, continuous 85 seating contact of the screen in its seat, as shown in Fig. 5.

The screen thus formed is entirely closed, both at its side and at its top where the leaves 90 11 are folded one over the other, and these folded and overlapped leaves may be subjected to compression, if desired, so as to set them in their final interleaved condition.

The screen in this condition will then be 95 mounted upon its supporting rod, as shown in Fig. 5. The supporting rod 19 will be passed through the overlapped leaves 11, but, prior to thrusting the end of the rod 19 through the leaves, there will be threaded upon it a disk or washer 20 which will be held in place in any suitable manner, but, preferably 100 as here shown, by compressing the rod

19 just below the washer so as to throw out a holding protuberance or burr 21 which will hold the washer 20 in proper position. The end of the rod 19 which is thrust through the top of the screen will extend sufficiently beyond the screen to permit a second washer 22 to be threaded thereon, and then the extreme end of the rod will be upset as shown, to provide a protuberance or burr 23, which will lock the washer 22 in place, and the screen will be held securely between the washers.

In event of the screen becoming corroded and worn, it may be very readily and quickly replaced by simply removing the washer 22, placing a screen upon the end of the rod, replacing the washer, and upsetting the end of the rod. As a matter of fact, the cost of rod 19 and washers 20 and 22 is so small that it is contemplated, when replacements are necessary, in strainers for which the screen is designed, to replace a corroded or damaged screen by a complete screen and supporting rod.

Screens made in accordance with my method and following the construction illustrated and described may be very rapidly and cheaply constructed by unskilled labor, and with a minimum of mechanical devices, it being necessary only to have equipment which will blank out of suitable stock the screen blank, provide the necessary seaming tools for forming the ends, and the mandrel and stamp for closing the interlocked screen.

Such minor changes in construction as are within the skill of the mechanic may be made and still be within the range of my invention.

I claim:

1. A strainer having a body-portion of reticulated material, and a leaf integral with said body-portion bent over and closing an end of said body-portion.

2. A strainer having a body-portion of reticulated material, and leaves integral with said body-portion bent over in lapped relation and closing an end of said body-portion.

3. A strainer having a body-portion of reticulated material formed at its ends to form a continuous side wall, and leaves integral with said body-portion bent over in lapped relation and closing an end of said body-portion.

4. A strainer having a body-portion of reticulated material lock-seamed at its end to form a continuous side wall, and leaves integral with said body-portion bent over in lapped relation and closing an end of said body-portion.

5. A strainer having a body-portion of reticulated material lock-seamed at its ends to form a continuous side wall, leaves integral with said body-portion bent over in lapped relation and closing an end of said body-portion, and fastening means for said leaves.

6. A strainer having a body-portion of re-

ticulated material lock-seamed at its ends to form a continuous side wall, leaves integral with said body-portion bent over in lapped relation and closing an end of said body-portion, and fastening means passing through said lapped leaves.

7. A strainer having a body-portion of reticulated material lock-seamed at its ends to form a continuous side wall, leaves integral with said body-portion bent over in lapped relation and closing an end of said body-portion, and a strainer supporting rod the upper end of which engages and fastens said lapped leaves.

8. A strainer having a body-portion of reticulated material lock-seamed at its ends to form a continuous side wall, leaves integral with said body-portion bent over in lapped relation and closing an end of said body-portion, and a strainer supporting rod the upper end of which passes through and fastens said lapped leaves.

9. A strainer formed of a single piece of reticulated material with a side seam joining its ends disposed interiorly of the strainer to give an unbroken exterior wall and infolded overlapped leaves closing one end.

10. A strainer blank of reticulated material having a plurality of integral leaves projecting from its edge.

11. A strainer blank of reticulated material having a plurality of integral leaves with rounded ends projecting from its edge.

12. A strainer blank of reticulated material having a plurality of integral leaves at an edge and seam forming sections at its ends.

13. A strainer blank of reticulated material having a plurality of integral leaves at an edge and seam forming sections of unequal lengths at its ends.

14. A sector-shaped strainer blank of reticulated material having a plurality of integral leaves projecting from one edge.

15. A sector-shaped strainer blank of reticulated material having a plurality of integral leaves projecting from its concave edge.

16. The method of making strainers, which consists in forming a blank with integral leaves at one edge, bending the blank to shape, securing the ends of the blank together, and infolding said integral leaves in overlapped relation.

17. The method of making strainers, which consists in forming a blank with integral leaves at one edge, bending the blank to shape, lock-seaming the meeting ends of the blank together, infolding said integral leaves in overlapped relation, and fastening such overlapped leaves together.

18. The method of making strainers, which consists in forming a blank with integral leaves at one edge, bending the blank to shape, lock-seaming the meeting ends of the blank together with the seam lying within

the strainer, infolding said integral leaves in overlapped relation, and fastening such overlapped leaves together.

19. The method of making strainers, which
5 consists in forming a sector-shaped blank with integral leaves at one edge and end portions of unequal lengths, lock-seaming the end portions together with the seam wholly

within the strainer, infolding said integral leaves in overlapped relation, and securing ¹⁰ such overlapped leaves together by a strainer supporting rod passed therethrough.

In testimony whereof I have hereunto set my hand.

PHILIP MUELLER.
